UNITED STATES PATENT OFFICE.

KARL IRWIN HERMAN, OF CHICAGO, ILLINOIS.

CARTON-BLANK.

1,159,024.

Specification of Letters Patent.

Patented Nov. 2, 1915.

Application filed July 25, 1914. Serial No. 853,076.

To all whom it may concern:

Be it known that I, KARL IRWIN HERMAN, a citizen of the United States, residing at Chicago, in the county of Cook and State 5 of Illinois, have invented new and useful Improvements in Carton-Blanks, of which the following is a full, clear, concise, and exact description, reference being had to the accompanying drawing, forming a part of 10 this specification.

My invention relates to improvements in carton blanks and one of the objects thereof is to provide a carton blank comprising a unitary flat sheet which may be folded into 15 a completely closed carton representing a gable-roof house.

Another object of my invention is to provide a carton blank which may be shipped flat and which may be readily and easily 20 set up or folded to form the carton.

For the purpose of disclosing my invention I have illustrated certain embodiments thereof in the accompanying drawings, in which—

25 Figure 1 is a plan view of a carton blank embodying my invention; Fig. 2 is a plan view of a modification of the blank illustrated in Fig. 1; Fig. 3 is a perspective view of a carton showing the same folded in imitation of a gable-roof house; and Fig. 4 is an enlarged detail section taken on the line 4—4 of Fig. 1, showing the manner in which the carton is held together.

In the embodiment illustrated in Fig. 1, 35 the blank comprises a single sheet of cardboard of suitable thickness and is substantially T-shaped in form, the leg 1 of the T being scored or creased at 2, 3 and 4 transversely to form, respectively, when folded, a side 5 and the two gable sections 6 and 7. The T head is creased transversely at 8 to form the bottom 9 and the side 10. It is also creased longitudinally at 11 and 12, which creases, it will also be noted, extend to the 40 parts 5, 6 and 7. The two longitudinal creases 11 and 12 form the ends 13 and 14 and oppositely disposed side flaps 15 and 16, the side flaps being scored and separated from the part 10 by the cuts 17 and 18. The 45 two end pieces 13 and 14 are pointed, as at 19, and the end pieces are provided with end flaps 20 which turn down and form a securing means, these flaps being slotted to receive fasteners, or the like. The side member 5 is provided with end flaps 21 which are turned at right angles thereto and are

also slotted to receive fastening devices, such as McGill fasteners or the like. In folding, the two end pieces 13 and 14 are turned vertically, and with them the side flaps 16 and 17. The end flaps 21 are turned at right angles to the side member 5 and the side member then turned vertically, suitable fasteners being inserted between the slots in the end members and the slots in the flaps. 60 The flaps 20 are turned down and the top or roof sections 6 and 7 are turned over the pointed ends 19 of the end members, suitable fasteners being inserted through the slots in the member 7 and into the fastening flaps 70 20. The device when thus folded assumes a form illustrated in Fig. 3, with the two side flaps 15 and 16 opened and the portion 9 and 10 forming the bottom and front porch of the house, the two side flaps 15 and 16 75 forming the doors. When it is desired to close the carton the two side flaps 15 and 16 are folded inwardly and the bottom or porch section 10 is folded upwardly, thereby completely closing the carton. 80

In the structure illustrated in Fig. 2, the blank is cut to form one side 1, the gable roof 2 and 3, and the end members 13 and 14 are connected at their top along one of the inclined sides, as at 22, the side flaps 85 15 and 16 extending from these end members. The bottom 9 and other side member 10 are the same as in Fig. 1. This figure, it will be noted, is also substantially T-shaped, but the scoring and cutting is 90 slightly different. In folding, the end members 13 and 14 would be folded at right angles to the gable top section 2, which would lay them endwise and extending vertically with respect to the side member 1. 95 When the side member 1 is turned up vertically, then, of course, the end members will assume their correct position. Instead of providing holding flaps 20, as in Fig. 1, the holding flaps 23 are secured to the top section 3 and are folded down to fasten to the end members 13 and 14. 100

I have shown the end members 13 and 14 as being integrally formed with the leg to the T, but it will be understood that if it is 105 desired these end members may be cut separately and then stitched or stapled in position.

Having thus described my invention, what I claim as new and desire to secure by Letters Patent, is:—

A blank for forming a carton, which car-

ton is shaped to resemble a building having a floor, two sides, two ends and a gable roof, said blank comprising a substantially rectangular portion divided into five rectangular sections to form a bottom section, two roof sections and two side sections, said blank comprising also four pentagonal wing sections extending laterally on opposite sides from said rectangular portion to form end sections, and two rectangular portions one extending laterally from each of said end sections to form door sections, one of said

side sections being located so that it can be turned down to form a porch section, said door sections being of sufficient extent to close the side of the carton when the side section is used as a porch.

In witness whereof, I have hereunto subscribed my name in the presence of two witnesses.

KARL IRWIN HERMAN.
